Application July 22, 1939, Serial No. 285,946
In Austria May 9, 1938

4 Claims. (Cl. 41—10)

The present invention relates to decorative articles more particularly to articles in which an ornamental element is moulded to support or tie means.

The object of the present invention is the provision of decorative articles comprising at least one element made of plastic material and element mounting means which is or are embedded in said element while it is formed. The mounting or tie means consist, for example, in threads or wires, on which decorative plastic members are arranged and equally spaced apart, so that with a multiple row arrangement of said elements and tie means, tapes or flat shaped ornamental screen-like materials are obtained, which may be used for the decoration of dresses and objects of use such as hand bags, mats, etc., as well as for the direct production of such objects. As plastic masses for the production of decorative articles according to the present invention preferably warm plastic or heatable synthetic masses are employed, but sprayable metal may also be used. The production of such decorative articles is performed by mass production in suitable moulds for casting, spraying, pressing or pressure casting methods, provided with hollow spaces for a group of decorative elements and arranged for the insertion of parallel cross threads, wires, webs or the like which connect the decorative elements with one another.

The increasing use of such decorative articles in the form of tapes or flat shaped structures appears to make it desirable to make them also of larger dimensions, whereby, however, the corresponding greater weight of the main members, particularly in comparison with the relatively fragile connecting or tie means, is a drawback.

According to the invention, the above mentioned disadvantage is overcome and at the same time the cost of production is reduced, by the formation of cavities in the underside and opening to the rear of the moulded members or elements, which cavities do not in any way change the appearance of the front portion which is exposed to view of the decorative article but result in a substantial saving in mass and weight. Moreover, the time needed for hardening of the moulded bodies is considerably reduced because of the small mass of the bodies. Such a construction of the moulded members is made to suit the arrangement and position of the mounting means, in that the mounting means consisting in threads or wires is arranged to extend through locally strengthened walls of the decorative element or is laid in masses bridging over

the hollow spaces. Where such an arrangement is not possible on account of the cross-sectional configuration of the moulded member, or if as mounting material web or the like is employed, the mounting means according to the invention is embedded in the mass of the upper surfaces of the hollow chambers.

In order that the invention may be more readily understood and practised, some embodiments thereof will now be described with reference to the accompanying drawing, in which:

Figure 1 illustrates a cross-section through a moulded member according to the present invention;

Figure 2 is a perspective view, from below, of moulded members according to Figure 1 and being interconnected by threads;

Figure 3 is an isometric showing of modified moulded elements according to the present invention and being interconnected by tie means;

Figure 4 is a bottom view of another modification of the present invention;

Figure 5 is a cross-sectional view of a further modification of the present invention;

Figure 6 illustrates an underside perspective view a rectangular decorative article according to Figure 5;

Figure 7 illustrates in section the arrangement of a web as the mounting means for and extending through a row of decorative members.

For a preferred imitation of pearl webbing, a spherical segmental form of a decorative member according to Figure 1 is provided which has a cylindrical hollow space 1 open underneath and arched over by a relatively thin cap 2. The threads 3 serving as mounting or tie means are disposed in the strengthened lower portions of the walls. In the underside view, Figure 2, the decorative elements have a basin-like appearance.

In the construction according to Figure 3, a further saving in mass and weight is obtained by limitation of the wall strengthening to the parts through which the threads extend. The moulded members consist in thin walled caps, the hollow spaces of which are limited only on opposite sides by plane surfaces 4, whereby the necessary material thickness is obtained for embedding the threads.

In order to be able to arrange also crossed threads as mounting means, according to Figure 4 interior walls 5 are provided as bridge pieces within the hollow chamber through which the threads 3 extend. An example of this embodiment

ment of the present invention is illustrated in Figure 4.

The embodiment according to Figures 5 and 6 differs only in shape from those of Figures 1 and 2, being in this case of pyramid form 6. The lower parts of the moulded member through which the threads extend are strengthened to form a kind of frame.

The moulded members illustrated in Figure 7 are of a shape which does not allow room for the passage of threads or wires. In such a case the mounting means extends through the walls of each moulded member over the surface of the hollow space in which it is embedded during moulding. The mounting means employed with such a form of connection of the moulded members 7 may also be a webbing 8, as illustrated in Figure 7. The arching of the webbing is effected without difficulty by means of the corresponding part of the casting mould, prior to removal of the moulded members. Should the webbing not be sufficiently expansible, for example, if it is composed of wire, it is previously shaped. The arrangement illustrated in Figure 7 is suitable, for example, for mats which have to form a base for cooking vessels or crockery; for the ornamental element a material is selected which can resist heat.

Because of the smaller mass and larger surface of the moulded members according to the present invention, due to the provision of the cavities, setting in the mould is accelerated, resulting in a saving of working time. The moulds can be opened almost at once after the material is pressed, and the finished decorative articles removed. Certain disadvantages of solid and therefore slow setting moulded members, such as, in particular, the occurrence of sunken places on the surface are avoided when practising the present invention.

What is claimed is:

1. As an article of manufacture a one-piece

ornamental element made of mouldable material adapted to be strung on thread or wire like support means, said element having an ornamental front portion and a permanently open cavity at its rear reducing the weight and the time for cooling and hardening of said element.

2. As an article of manufacture a one-piece ornamental element made of mouldable material adapted to be strung on thread or wire like support means, said element having an ornamental front portion and a permanently open cavity at its rear reducing the weight and the time for cooling and hardening of said element, said cavity leaving a relatively thin wall portion in the ornamental front portion of said element and a relatively thick rim portion in the rear of said element receiving and completely embedding said support means.

3. As an article of manufacture a one-piece ornamental element made of mouldable material adapted to be strung on thread or wire like support means, said element having an ornamental front portion and an unrestricted cavity permanently open at its rear for reducing the weight and the time for cooling and hardening of said element, said cavity leaving a wall portion of substantially equal thickness in the front of said element and a rim portion having thickened parts extending into said cavity and receiving and completely embedding said support means and providing additional strength of the parts receiving the support means.

4. As an article of manufacture a one-piece ornamental element made of mouldable material adapted to be strung on thread or wire like support means, said element having an ornamental front portion and an unrestricted cavity permanently open at its rear, and web portions traversing said cavity for receiving and embedding said support means.

DANIEL SWAROVSKI.
